Specification for Design.

Patented May 23, 1922.

Application filed January 15, 1919. Serial No. 271,330. Term of patent 3½ years.

To all whom it may concern:

Be it known that I, THOMAS M. OBSBOUM, a citizen of the United States, and a resident of the city of Chicago, county of Cook, and State of Illinois, have invented a new, original, and ornamental Design for Rings, of which the following is a specification, reference being had to the accompanying drawings, forming a part thereof.

Fig. 1 is a front elevation of a ring illus-

trating my design, and Fig. 2 is a side elevation of the same.

I claim:

The ornamental design for a ring, as shown.

THOMAS M. OBSBOUM.
